United States Patent Office

Des. 188,426
Patented July 19, 1960

188,426

BALL PROJECTILE GAME DEVICE

Albert S. Hayden, Darlington, Md.

Filed Sept. 8, 1959, Ser. No. 57,458

Term of patent 7 years

(Cl. D34—15)

The single figure is a perspective view of the ball projectile game device.

The side not shown is substantially the same as the side shown.

The broken line showing of a ball is for illustrative purposes only.

I claim:

The ornamental design for a ball projectile game device, as shown and described.
